UNITED STATES PATENT OFFICE.

HIRAM H. SHELTERS AND HARLEY A. BASHAW, OF BURLINGTON, VERMONT; SAID BASHAW ASSIGNOR TO SAID SHELTERS.

LEAF-SPRING OILER.

Application filed November 23, 1921, Serial No. 517,264. Renewed May 22, 1924.

To all whom it may concern:

Be it known that we, HIRAM H. SHELTERS and HARLEY A. BASHAW, citizens of the United States of America, and residents of 5 Burlington, county of Chittenden, and State of Vermont, have invented certain new and useful Improvements in Leaf-Spring Oilers, of which the following is a full and clear specification.

10 The object of this invention is to provide a simple and inexpensive flexible envelope for oiling leaf-springs, the device being oil-proof, dirt-proof and water-proof, as more fully hereinafter set forth.

15 Fig. 1 is a perspective view of a part of a leaf spring showing our device applied thereto;

Fig. 2 is a transverse sectional view thereof;

20 Fig. 3 is a perspective view of the cover unfolded.

In the drawing, 5 designates the outer fabric of the envelope which may be leather, leatherette, oil-cloth or any fabric which is 25 waterproof. This fabric is provided along one longitudinal edge with a hem which encloses a metal rod 6, and along its two end edges it is hemmed for the purpose of receiving in each hem a draw-string 7. Af-

30 fixed to the inner face of the outer fabric 5 are two paper sheets, one, 8, next to the fabric being waterproof, and the other one, 9, being oil-proof. The ends of each of these sheets are fastened to the fabric by being stitched 35 within the draw-string hem, as shown. At one longitudinal edge, the sheet 8 is provided with a flap 10, the longitudinal and end edges of this flap being hemmed and stitched for the purpose of preventing tearing and 40 also for the purpose of receiving a series of headed metallic fasteners 11.

The other, oil-proof, sheet 9 is also provided with a flap 12 which is considerably wider than the flap 10, being wide enough 45 to project beyond the wired edge of the main fabric 5 when opened out flat. Attached to the face of this flap by lines of stitching 13 is a felt pad 14 consisting of one or more thicknesses of ordinary oil-absorbing felted material.

50 The envelope constructed as above described is folded about the leaves composing the spring, the pad being wide enough to extend across the top (or the bottom) surface of the spring and along the edges there-

of. When thus applied to the spring, the oil carried by the pad will, as the spring vibrates and works under load strains, seep into the crevices between the leaves and thus keep them well lubricated. In thus fastening the envelope to the spring, the flap 12 is first folded about the spring; then the flap 10 is folded upon the flap 12 so as to cause the pointed fastening-pins 11 to be pointed away from the spring; then the unbound edges of the fabrics 5, 8 and 9 are folded over upon the fastening devices and pressed down thereon so as to cause the fastening-pins to puncture all the thicknesses; then the wired edge of the main fabric is finally folded over upon the fastening devices and pressed down thereon so as to be punctured thereby; then the projecting ends of the fastening devices are bent down in the manner of paper fasteners to secure 70 the parts in folded relation. Then, as a final securing means, the draw-strings are drawn taut and tied, so as to thereby tightly close the ends of the envelope against dirt and dust. The wire 6 prevents the outer edge 80 of the fabric 5 from folding or puckering, thus maintaining a tight dust-proof joint along the entire longitudinal edge of the envelope.

85 It will be observed that the device may be readily removed by straightening the pointed ends of the fasteners so as to permit the various fabrics to be pulled off the points of the fasteners; and then the device may be reapplied in the same manner 90 after a fresh supply of oil is given to the pad.

95 It will be observed that our device is simple and inexpensive, easily applied and removed, and practically dust- and water-proof. It will be observed also that the manner in which the oil-pad is unfolded ensures against any material evaporation or leakage of the oil and that a thorough and uniform lubrication of the leaves of the 100 spring will be maintained so long as the oil-supply lasts.

105 It will be observed also that the unsightliness due to leakage of oil and deposit of dust and dirt, which is common to the devices now on the market, is entirely avoided and that, therefore, our device will at all times have a neat and clean appearance.

110 Another feature of importance is that a dealer by carrying in stock a reasonable

- number of sizes may fit the springs of any one of the stock cars now on the market, thereby rendering it unnecessary to carry a large supply of sets for different cars; 5 this is rendered possible by reason of the adjustability of the fastening arrangement and by providing for taking care of any surplus width through the medium of the wide outer flap.
- 10 The nature and scope of the invention having been thus indicated and its preferred embodiment having been specifically described, what is claimed as new is:
1. An oiling envelope for springs consisting of a main water-proof fabric having a draw-string attached to each end and having also a stiffening member attached to one of its longitudinal edges, an oil-pad attached to the inner face of said fabric, and 15 a flap attached to the inner face thereof and carrying fastening devices adapted to engage the stiffened edge of said main fabric, for the purpose set forth.
  2. An envelope for leaf-springs embodying a waterproof main fabric, an oil-carrying pad attached to the inner face thereof, a flap also attached to the inner face of the inner fabric and carrying fastening devices, 20
- one edge of said main fabric being provided with a hem which encloses a stiffening rod, for the purpose set forth. 30
3. An oiling envelope for springs consisting of a main fabric, a waterproof fabric affixed to the inner face thereof and having a flap formed along one edge, said flap being provided with a series of outwardly-directed fastening devices adapted to pass through the main fabric along one edge thereof, an oil-proof sheet also affixed to the inner face of said main fabric and having a free flap along one edge, and an oil-absorbing pad carried by this latter flap. 35
4. A spring oiling appliance consisting of a flexible envelope, a wire extending along one edge thereof, an oiling pad fastened to the inner face of the envelope, and means for fastening the envelope upon the spring with said wired edge lying on and pressed against the outside of the opposite edge of the envelope, to thereby insure a tight joint 40 throughout the length of the envelope. 45

In testimony whereof we hereunto affix our signatures this 18th day of November, 1921.

HIRAM H. SHELTERS.
HARLEY A. BASHAW.
